UNITED STATES PATENT OFFICE.

JOSHUA H. BEAVERS, OF NEW CASTLE, ASSIGNOR OF ONE-HALF TO
CHARLES M. REED, OF FAYETTE COUNTY, INDIANA.

FENCE-MACHINE.

SPECIFICATION forming part of Letters Patent No. 352,111, dated November 9, 1886.

Application filed March 1, 1886. Serial No. 193,652. (Model.)

To all whom it may concern:

Be it known that I, JOSHUA H. BEAVERS, a citizen of the United States, residing at New Castle, in the county of Henry, State of Indiana, have invented a new and useful Machine for the Building and Construction of Fences; and I do declare the following to be a full, clear, and exact description of the same, such as will enable others skilled in the art to which it appertains to make and use the same, reference being had to the accompanying drawings and the letters and figures of reference marked thereon, which form a part of this specification.

My invention relates to improvements in fence-building machines; and the objects of my machines are, first, to build a fence with pickets and wire, in which the wire, not being twisted, or twisted but once, at the option of the operator, can be taken down and used a second time, or oftener, if desired; second, to build a fence in which the wire will have a uniform tension throughout; and, third, to furnish a machine in which the tension is self-adjusting, and the whole of which shall be inexpensive. I attain these objects by the mechanism illustrated by the accompanying drawings, in which—

Figure 1 is a view of the entire machine set up ready to operate. Fig. 2 is a front view of the tension device; and Fig. 3 shows the arm and hasp-shaped semicircular piece carrying the block by which the wire is manipulated, which, for convenience of reference, I call the "hand."

My machines consist of the perpendicular staff *a*, the arms *b b*, the hands *c c*, the blocks *d d*, and the pivots of the hand *e e*, and pivots of the block *n n*, which constitute my machine for weaving the wire.

My tension device consists of the perpendicular frame-pieces *ff*, the base-piece *g*, and the rollers *i i*, the journals *jj*, the bolts *ll*, and the keys *mm*.

My machines are constructed and operated as follows, to wit:

The arms *b b* are composed of two pieces, one end of each of which is dovetailed into the sides of the perpendicular staff *a*. The hand *c* is a cast-iron, nearly semicircular, piece, the wrist of which exactly fits the space between the two pieces of the arm *b*, and is one-third that size at the other end. It is connected with the arm

by the pivot *e*, the other end or point of the hand *c*, being inserted in a slot in the block *d*, and attached thereto by means of the pivot *n*. 55

My tension device is constructed as follows, to wit: The perpendicular frame-pieces *ff* are inserted in the base-piece *g*. The journals *jj* are inserted in the perpendicular frame-pieces, which are held to their places by means of the bolts *ll*. The rollers *i i*, resting upon the journals *jj*, are concaved at the end for the purpose of giving an even pressure in the entire circumference of the roller against the side of the perpendicular pieces *ff*. The keys *mm* 65 are inserted in a mortise through the journals *jj*, which keys bear against the side of the perpendicular pieces *ff* with sufficient force to keep the wire taut when wound about the rollers in building the fence. The mortises 70 through the journals are cut in such a way as to permit the keys *mm* to draw the journals *jj*. *k* is a simple crank placed upon the journals *jj*, for the purpose of turning the rollers.

My machines are operated by placing the 75 tension device at the farthest point to which the fence is desired to be built, or upon the line upon which the fence is desired to be built at any convenient point thereof, driving the stakes *h h* into the ground through or in front 80 of base-piece *g*, and otherwise substantially fastening the tension device, to prevent its being moved by the wire in tightening. The amount of wire which will probably be consumed by crossing and twisting the wire about 85 the pickets is then wound around the rollers, and the other end of the wire is then carried back and fastened to a post at the end from which it is desired to build the fence. The wire is then tightened by means of the crank 90 *k* on the journals *jj*, turning the rollers *i*. The machine for twisting or crossing the wire is now placed upon the wire by inserting the wire upon the upper roller, *i*, in the notch *o* in the lower end of the block *d*, and the wire from the 95 lower roller of the same series of rollers in the upper end of the same block. The wires being thus placed, by moving the perpendicular staff *a* either upward or downward, as the case may be, the hand *c* is caused to describe a complete circle, less the width of the arm *b* upon the pivot *e*, and the block *d* describes about one-fourth of a circle, thus twisting the wire, or, if it is desired, only crossing the wire.

The perpendicular staff *a* is moved upward or downward only one half of the distance until the hand *c* has described nearly a half-circle, when a picket is inserted between the wires. 5 The perpendicular staff is then moved on until the hand has described a complete circle, less the width of the arm, thus alternately crossing the wires above and below each other.

I claim—

10 1. The combination of the staff *a*, the arms *b b*, as herein described, the hands *c c*, the pivots *e e*, and the blocks *d d*, with the pivots *n n*.

2. The combination of the perpendicular frame-pieces *f f*, the base *g*, the stakes *h h*, the rollers *i i*, the journals *j j*, the crank *k*, the bolts *l l* and the keys *m m*, all substantially as set forth and described, for the purposes herein named.

JOSHUA H. BEAVERS.
